UNITED STATES PATENT OFFICE.

FRANCIS CHARLES EDWARD BURNETT AND ERNEST JOHN BRUNNING, OF MONTREAL,
QUEBEC, CANADA.

ELECTRIC HEATING DEVICE.

1,234,280.

Specification of Letters Patent. Patented July 24, 1917.

Application filed November 27, 1916. Serial No. 133,698.

To all whom it may concern:

Be it known that we, FRANCIS CHARLES EDWARD BURNETT and ERNEST JOHN BRUNNING, both subjects of the King of Great Britain, and residents of the city of Montreal, in the Province of Quebec, Dominion of Canada, have invented certain new and useful Improvements in Electric Heating Devices, of which the following is a specification.

This invention relates to improvements in electric heating devices and particularly to such devices as may be employed for the heating of metallic rings, having particular reference to the copper or other bands used at the base of shells for the purpose of engaging the rifling of the gun. It is obvious, however, that the method here described is applicable to the heating of any complete circuit of metal for the tempering or annealing or other purposes.

It has already been proposed to heat metallic rings in a device in which the rings constitute the secondary circuits of a transformer. The objects of the present invention are to provide improvements in this apparatus, to secure more satisfactory and accurate operation thereof under commercial conditions, and to make such improvements in the electrical connection which will enable the various circuits to be regulated to suit conditions. The invention comprises the improved construction and arrangement of parts hereinafter described in detail in the accompanying specification and drawings.

In the drawings:

Figure 1 is a sectional elevation through an embodiment of the invention.

Fig. 2 is a cross section on the line 2—2, Fig. 1.

Fig. 3 is a side elevation with the refractory chamber for the ring to be heated removed, and having the wiring indicated diagrammatically.

Fig. 4 shows diagrammatically the electrical connection by which the voltage is regulated.

Fig. 5 shows diagrammatically the method employed to control the primary electric circuit.

In the drawings like characters of reference refer to corresponding parts in each figure.

Referring to the drawings, A represents

a magnetic core or circuit conveniently built up of suitable plates of iron or steel, and in the embodiment illustrated, being of rectangular form. A portion B, in this case the top portion of the core, is movable and is adapted to be raised and lowered by suitable means such as the lever C which is shown pivoted to a support D.

E represents a primary winding mounted on one side of the magnetic core and consisting of a suitable number of turns in a conductor wound in the usual way, current being supplied from the conductors 10 and 11.

It is important to insure that the circuit through the primary winding should not be completed until the movable part of the core is in exact position, as otherwise the back E. M. F. in the primary winding would not be great enough and the current would be too high.

To perform this function, I provide a contact 12 on the lever C adapted to cooperate with a suitable fixed and adjustable contact 13 on the support 14, the conductor 10 being connected to the contact 12 and a conductor 15 leading from the contact 12, the conductor 11 and conductor 15 being connected to the double pole switch 16 which is suitably connected to a source of electric power.

The movable part B need not exactly fit to the other part of the magnetic core, but small air gaps 20 and 21 may be left between and a further regulation in the amount of heating may be made by adjusting the amount of this air gap through the adjustment of the fixed contact 13 in any convenient way.

It will be observed that the reluctance of the magnetic circuit may be alternated at will to suit the needs of the case by varying the air gaps 20 and 21, or inserting pieces of non-magnetic material in these air gaps.

Surrounding the primary winding E, is a casing C of suitable refractory material adapted to contain the ring to be heated. This case is annular in form and serves the double purpose of minimizing the loss of heat from the material to be heated and protecting the primary winding and the magnetic core from injury, due to the heat radiated or conducted from the material to be heated.

H represents the ring to be heated and

which is located in the chamber G and will constitute the secondary circuit. The top or cover 24 of the refractory chamber is connected by suitable brackets 25 to the 5 movable part B and is adapted to move therewith.

In operation the lever C is raised, carrying the part B and cover 24. The metal ring H to be heated is then placed in the chamber G 10 and the switch 16 thrown into operative position and the lever C brought down. As soon as the contacts 12 and 13 meet the circuit will be completed through the primary winding E which will induce a heavy 15 current in the article H which forms the secondary in which heat may be maintained as long as the current is on. When the heating is completed, the switch 16 may be opened and the lifting of the part B will 20 carry the cover 24, permitting the removal of the heated article.

Under certain conditions it may be desirable to vary the voltage in the arrangement above described and the preferred 25 manner of doing this is shown in Fig. 4, in which E represents the primary winding in Fig. 1. 10' and 11' indicate connections from the winding E to a double pole switch 16. K represents auto-transformer having a 30 winding 30 on a magnetic core 31, the construction and operation of which is well known in the art and this transformer is in the circuit between the primary winding E and the switch 16.

If it is desirable to regulate the primary 35 circuit by non-inductive means, it may be done as shown in Fig. 5, in which E indicates the primary winding, 10² and 11², connections between it and a double pole switch 40 16, any one of which connections, such as 11², a non-inductive resistance 22 is inserted in series with the wire 11².

As many changes could be made in the 45 above construction and many apparently widely different embodiments of our invention, within the scope of the claims, constructed without departing from the spirit or scope thereof, it is intended that all matter contained in the accompanying specifica-

tions and drawings may be interpreted as 50 illustrative and not in a limiting sense.

What we claim as our invention is:

1. An electric heating device comprising in combination a rectangular magnetic core having a movable top portion, means for 55 raising and lowering the top portion, a primary winding mounted on one side of the magnetic core, an annular casing surrounding the primary winding adapted to contain the article to be heated, and a cover for the 60 casing connected to and movable with the movable part of the core.

2. An electric heating device comprising a magnetic core of rectangular shape having the upper side movable, means for adjustably 65 supporting the upper part in position and separating it by a slight gap from the other portion of the core, means for raising and lowering the movable part, a primary winding on the core, an annular chamber adapted 70 to contain the article to be heated and surrounding the primary winding.

3. An electric heating device comprising a magnetic core having a movable part, a primary winding, a secondary winding formed 75 by an article to be heated, and means preventing the completion of the current through the primary winding until the movable part of the magnetic core is in proper relative position to the other part. 80

4. An electric heating device comprising a magnetic core having a movable part, a primary winding, a secondary winding formed by an article to be heated, and means preventing the completion of the current 85 through the primary winding until the movable part of the magnetic core is in proper relative position to the other part, said means comprising a fixed contact and a movable contact moving with the movable 90 part.

In witness whereof we have hereunto set our hands in the presence of two witnesses.

FRANCIS CHARLES EDWARD BURNETT.
ERNEST JOHN BRUNNING.
